Primary Examiner — Susan E Krakower*Assistant Examiner* — Jerry Shiuan-Hua Hsu(74) *Attorney, Agent, or Firm* — TROUTMAN PEPPER HAMILTON SANDERS LLP(57) **CLAIM**

The ornamental design for a quarter window scoop, as shown and described.

DESCRIPTION

FIG. 1 is a perspective view of the quarter window scoop of the present invention, the opposite side window scoop being a mirror image thereof;

FIG. 2 is a perspective view of the mirror image, of the quarter window scoop shown in FIG. 1;

FIG. 3 is a front view of the quarter window scoop shown in FIG. 1;

FIG. 4 is a rear view thereof;

FIG. 5 is a top view thereof;

FIG. 6 is a bottom view thereof;

FIG. 7 is a front elevation view thereof;

FIG. 8 is a rear elevation view thereof; and,

FIG. 9 is a perspective view thereof, shown in a condition of use.

The broken lines illustrate environmental structure and forms no part of the claimed design.

1 Claim, 9 Drawing Sheets(56)
